UNITED STATES PATENT OFFICE

JOHN A. RYMER, OF SAN LEANDRO, CALIFORNIA, ASSIGNOR TO RY-LOCK COMPANY, LTD., OF SAN LEANDRO, CALIFORNIA, A CORPORATION OF NEVADA

DOORLOCK

Application filed September 3, 1932. Serial No. 631,606.

This invention relates to improvements in door locks of the latch bolt type used on outside doors, and of that general character in which the external door knob is normally disconnected from the interior knob and from the bolt spindle and which can be connected to the spindle at will from inside the door.

A lock of this type is disclosed in my Patent No. 1,834,223, dated December 1, 1931. In this previous lock however the engagement of the outer knob with the bolt spindle was had by an axial movement of the spindle and the inner knob and this was found to be an objectionable feature for various reasons. The structure of the present invention therefore particularly represents improvements over this previous one; my principal object being to retain all the advantageous features of the previous form of lock by providing a releasable interlocking means between the outer knob and the spindle arranged to be actuated at will without any axial movement of the spindle or either knob being necessary.

The above and other objects will be apparent from a perusal of the following specification in connection with the drawings accompanying the same.

These objects I accomplish by means of such structure and relative arrangement of parts as will fully appear by a perusal of the following specification and claims.

In the drawings similar characters of reference indicate corresponding parts in the several views:

Figs. 1 and 2 are top plan views of the lock structure partly in section, showing the position of the parts when the outer knob is respectively disengaged from and engaged with the bolt spindle.

Fig. 3 is a cross section on the line 3—3 of Fig. 2, the lock being detached from the door.

Fig. 4 is a perspective view of various parts of the lock disposed in the proper relation to each other but shown separated for clearness.

Fig. 5 is a perspective view of the outer knob and bolt spindle unit.

Fig. 6 is a sectional plan of the outer knob and spindle interlocking mechanism associated therewith, the knob being locked against rotation and the spindle being turnable relative thereto.

Fig. 7 is a cross section on the line 7—7 of Fig. 6.

Fig. 8 is a view similar to Fig. 6 showing the knob unlocked or free to rotate and engaged with the spindle.

Fig. 9 is a cross section on the line 9—9 of Fig. 8.

Fig. 10 is a sectional plan of the shifting sleeve and retaining plate unit.

Fig. 11 is a perspective view of the rotary sleeve actuating member looking from the inside.

Fig. 12 is a similar view of the member looking from the outside.

Referring now more particularly to the characters of reference on the drawings, the numerals 1 and 2 denote the outer and inner escutcheon plates of the lock, abutting against the opposed faces of the door 3 near its free edge and surrounding a circular opening 4 drilled through the door. Another relatively small opening 5 for the bolt housing 6 is drilled from said edge of the door to the opening 4 axially thereof.

A collar 7 about the sleeve 8 of the outer knob 9 is rigidly secured by screws 10 to a circular orificed plate 11 which is recessed into the inner face of the plate 1. A sleeve 8 is rigidly secured to the knob and adjacent its inner end is provided with an external circumferential groove 12 which is engaged by a segmental retaining washer 13 disposed between the plate 11 and the collar 7 and held in place by the screws 10. The knob 9 can therefore turn but cannot be displaced axially.

The bolt spindle 14 of the usual square form projects through the actuator 15 of the latch bolt 16. This actuator is turnable in the housing 6 and is operatively connected to the bolt in the same manner as shown in my previous patent. At its inner end the spindle non-turnably engages the sleeve 17 of the inner knob 18 to which it is removable.

bly secured by a screw 19 in the customary manner.

At its outer end the spindle has swivel jointed connection with an extension 20 formed at its outer end with an enlarged flange 21. The extension has a transverse notch 22 in its outer end adapted to be engaged by the tip of the proper key inserted in the barrel 23 of a lock of standard character which is mounted in the outer knob. This arrangement enables the spindle to be turned and the door to be opened whether the outer knob is free to turn at the time or not. A cup 24 seated in the outer end of the sleeve 8 against inward movement engages the flange 21 to prevent inward movement of the spindle; outward movement being prevented by the engagement of the notched end of the flange with the adjacent end of the lock barrel.

Slidable on the spindle and its extension and in the sleeve 8 is an inner sleeve 25, normally urged outwardly or against the cup 24 by a spring 26. The bore of the sleeve 25 at its inner end is of reduced size and is square as at 27 to slidably and non-turnably engage the spindle; said spindle in the plane of the normal position of the square portion 27 being rounded as at 28 or otherwise reduced in size so that it can turn in said portion 27. The contacting surfaces of the sleeves 25 and 8 where they slidably engage each other are of hexagonal or other non-circular form as at 29 so that they must turn together.

The inner end of the sleeve 25 is normally disposed inwardly of the plate 11 and the exposed portion of the sleeve is provided with longitudinal opposed slots 30. These slots are engaged by lugs 31 projecting from the bore of a ring 32, the lugs bearing against the back end of the slots. The ring is notched on its sides as at 33 to slidably but non-turnably engage lugs 34 struck up from and extending axially of the plate 11.

From the above description it will be seen that the spindle is normally turnable in the outer knob so that it cannot be turned by the rotation of said knob. On shifting the sleeve 25 lengthwise against the resistance of the spring 26 until the square bore 27 of the sleeve engages the square portion of the spindle, the knob and spindle are locked together and must turn as a unit. At the same time the sleeve 25 is moved so that the ring 32 is clear of the lugs 34, so that the knob can be turned. This movement is imparted to the sleeve from the inside of the door by the following means.

Turnably engaging the sleeve 25 immediately in front of the ring 32 and projecting radially therefrom is an arm 35, held against longitudinal movement on the sleeve by a snap washer 36. The arm 35 is connected to another radially extending arm 37 dis-

posed inwardly of or on the opposite side of the bolt housing 6 by a longitudinally adjustable connecting unit 38. This unit is preferably in the form of cooperating sleeve and screw members which extend parallel to the spindle and pass just behind the inner end of the housing 6, as shown in Fig. 3.

The arm 37 is rigid with an actuator sleeve 39 which surrounds the spindle in clearance relation thereto and which projects through the plate 2 and into a collar 40 which turnably engages the outer end of the knob sleeve 17. This collar is turnably mounted in the plate 2 and has an enlarged flange 41 on its end which cooperates with a shoulder 42 on said plate. The flange is turnably clamped between the shoulder and a spring washer 43 set in the plate 2 so as to prevent axial movement of the collar in either direction without interfering with its rotation.

Pressed into the collar and practically forming a part thereof is a plate 44 turnably engaging the sleeve 39 and holding the same centered on the spindle; said plate having opposed lugs 45 projecting from about the bore. These lugs engage opposite helical grooves 46 cut in the sleeve 39 so that as the collar 40 is turned said sleeve will be moved lengthwise, imparting a corresponding movement to the sleeve 25 through the various connecting elements.

The pitch and length of the helical grooves is such that with about half a turn of the collar the sleeve 25 will be moved to bring the square bore portion 27 over the square portion of the spindle and at the same time move the member 32 clear of the lugs 34, so that the plate and sleeve 25 are free to turn.

The rotative movement is thus imparted to the collar at will by a radial handle or knob 47 secured thereto in a convenient location preferably adjacent the plate 2. Rotation of the actuating sleeve 39 is positively prevented by means of lugs 48 engaging longitudinally extending grooves 49 in said sleeve. These lugs are mounted on a plate 50 countersunk in the plate 2 and bored to slidably guide the sleeve 39. The plate is mounted in a definite fixed position relative to the plate 11 and the various associated parts, and so that the arm 37 is radially parallel to the arm 35, by means of screws 51. These extend across the housing 6 above and below the same and engage ears 52 formed on the ends of spaced walls 53 projecting from the plate 11 and between which said housing projects. By means of this connection the plate 1 will be firmly clamped against the outer face of the door so that individual screws through the same are unnecessary, and the plate 50 is also firmly clamped against the inner face of the door.

The lugs 48 project inwardly of the bore

of the sleeve 39 as shown in Fig. 10 and serve as stops for one end of a compression spring 54 mounted in said sleeve about the spindle. The opposite end of the spring 5 bears against a shoulder 55 formed with the 5 arm 37 so that said spring tends to force the sleeve outwardly of or away from the plate 50.

When the sleeve 39 is drawn toward the 10 plate to a spindle coupling position by the rotation of the collar 40 it will remain in that position until the collar is intentionally retracted. Upon such retraction being affected the pull of the spring 26 causes the 15 ring 32 to re-assume its engaged position with the lugs 34 as soon as either knob and spindle are turned so that the notches 33 register with said lugs. This registration will take place before any knob turning 20 movement can be had after the collar has been once turned to its retracted position.

From the foregoing description it will be 25 readily seen that I have produced such a device as substantially fulfills the objects of the invention as set forth herein.

While this specification sets forth in detail the present and preferred construction of the device, still in practice such deviations from such detail may be resorted to 30 as do not form a departure from the spirit of the invention, as defined by the appended claims.

Having thus described my invention what I claim as new and useful and desire to secure by Letters Patent is:

1. In a lock of the latch bolt type, a bolt 40 actuating spindle, a knob secured to one end of the spindle, another knob having a sleeve into which the other end of the spindle projects, an inner sleeve about the spindle and slidably and non-turnably engaging the knob sleeve and arranged for non-turning engagement with the spindle only when said inner sleeve is moved from a predetermined position, a fixed plate about the inner sleeve, a member fixed on the inner sleeve, lugs projecting from the plate in the direction of sliding movement of the inner sleeve and non-turnably guiding said member, said lugs being shorter than the length of movement of the inner sleeve necessary to place the same in non-turning engagement with the spindle, and means actuatable at will for thus moving said inner sleeve.

2. In a lock of the latch bolt type, a bolt 45 actuating spindle, a knob secured to one end of the spindle, another knob in which the other end of the spindle is normally turnable, means for releasably locking said other knob to the spindle including a member movable axially of the spindle, a rotary control member mounted in connection with the one knob axially thereof, a sleeve about the spindle projecting into said rotary member, means supporting the sleeve concentric with

the spindle and guiding the same for axial movement, said sleeve having a helical groove cut therein, a radial lug on the rotary member engaging said groove whereby with the rotation of said rotary member the sleeve will be moved axially, and connecting means between said sleeve and the spindle locking member.

3. In a lock of the latch bolt type, a bolt 75 housing, a bolt actuating spindle projecting transversely through the housing, knobs on the ends of the spindle, the spindle being normally turnable in one knob, means for releasably locking said one knob to the spindle including a longitudinally movable sleeve on the spindle adjacent said one knob, a longitudinally movable actuating sleeve on the spindle adjacent the other knob, and direct connection means between said sleeves extending across the housing on the outside 80 of the same.

4. In a lock of the latch bolt type, a bolt 90 housing, a bolt actuating spindle projecting transversely through the housing, knobs on the ends of the spindle, the spindle being normally turnable in one knob, means for releasably locking said one knob to the spindle including a longitudinally movable sleeve on the spindle adjacent said one knob, a longitudinally movable actuating sleeve on 95 the spindle adjacent the other knob, radial and parallel arms projecting from said sleeves lengthwise of the housing past the back end thereof, and a rigid connection between the outer ends of the arms.

5. A structure as in claim 2 in which said connecting means comprises an arm rigid with and extending radially from the sleeve, an arm projecting radially from and turnable relative to said axially movable member of the structure for movement axially therewith, and a rigid connection between the outer ends of said arms.

6. A structure as in claim 4 with means 100 to alter the operative length of said connection from the exterior of the lock structure.

7. A structure as in claim 2 in which said sleeve supporting means comprises a plate 105 adapted to be secured against the face of a door, said plate having an orifice through which the sleeve slidably projects, and lugs projecting inwardly from said orifice, said sleeve having longitudinal slots with which the lugs engage.

8. In a lock of the latch bolt type a bolt 110 actuating spindle, knobs on the ends thereof, the spindle being normally turnable in one knob, means for releasably locking said one knob to the spindle including a member 115 movable axially of the spindle, a longitudinally movable actuating sleeve on the spindle adjacent the other knob, the bore of said sleeve being greater than the diameter of the spindle, a compression spring in the sleeve about the spindle, an element 120

rigid with the inner end of the sleeve against which one end of the spring bears, said sleeve having longitudinal slots open to the bore thereof, fixed lugs projecting through 5 the slots into the bore and against which the opposite end of the spring bears, and direct connection means between said sleeve and the axially movable member.

9. In a lock of the latch bolt type, a bolt 10 housing, an actuating spindle projecting transversely through the housing, knobs on the ends of the spindle, said spindle being normally turnable in one knob, means for releasably locking said one knob to the 15 spindle including an element on one side of the housing adjacent said one knob and movable to a predetermined position to effect such locking, an actuating member for the element on the opposite side of the housing 20 and adjacent said other knob, and connect-

ing means between said member and element extending across the housing exteriorly thereof.

10. In a lock of the latch bolt type, a bolt 70 actuating spindle, a knob secured to one end of the spindle, another knob about the other end of the spindle, a sleeve non-turnably and slidably mounted in connection with said other knob and into which the adjacent end of the spindle slidably projects, said 75 sleeve being arranged for non-turning engagement with the spindle when shifted a predetermined distance, an actuating sleeve mounted in connection with the one knob separate from the spindle and through 80 which the latter freely projects, and connection means between the sleeves exteriorly of the spindle.
